UNITED STATES PATENT OFFICE

EDWARD ROY FRYER, OF KENMORE, NEW YORK

DESIGN FOR COMBINED FENDER AND LAMP CASINGS FOR VEHICLES

Application filed September 11, 1929. Serial No. 32,722. Term of patent 14 years.

To all whom it may concern:

Be it known that I, EDWARD ROY FRYER, a citizen of the United States of America, and resident of Kenmore, in the county of Erie and State of New York, have invented a new, original, and ornamental Design for Combined Fender and Lamp Casings for Vehicles, of which the following is a specification, reference being made to the accompanying drawing, forming a part thereof.

In the drawing, Figure 1 is a perspective view and Figure 2 is a front elevational view showing my new design.

I claim:

The ornamental design for combined fender and lamp casings for vehicles substantially as shown.

Signed by me at Buffalo, New York, this 6th day of September, 1929.

EDWARD ROY FRYER.
